UNITED STATES PATENT OFFICE.

GEORGE M. SCHEBLER, OF INDIANAPOLIS, INDIANA, ASSIGNOR TO FRANK H. WHEELER, OF INDIANAPOLIS, INDIANA.

AIR-VALVE FOR CARBURETERS.

1,108,246.

Specification of Letters Patent. Patented Aug. 25, 1914.

Original application filed February 5, 1912, Serial No. 675,429. Divided and this application filed June 27, 1912. Serial No. 706,182.

To all whom it may concern:

Be it known that I, GEORGE M. SCHEBLER, a citizen of the United States, residing at Indianapolis, in the county of Marion and 5 State of Indiana, have invented a new and useful Air-Valve for Carbureters, of which the following is a specification.

The object of my invention is to produce improvements in details of construction of 10 an air inlet valve of a carbureter.

This case is a division of my co-pending application Serial No. 675,429, filed February 5, 1912.

The accompanying drawing illustrates my 15 invention.

The single figure of the drawing is a central vertical section through a carbureter embodying my invention.

In the drawing, 10 indicates a bowl-like 20 fuel chamber of substantially common form. At its bottom, this chamber is perforated at 13, and through this perforation is projected the lower end of a hollow stem 14 which is carried by the lower end of a main body 15 25 within which a mixing chamber or passage 16 is formed. The lower end of stem 14 is closed by a removable threaded plug 20, to permit drainage of the settling chamber or sump 21 thus formed in such lower end.

30 Surrounding the lower end of stem 14 is a primary air inlet structure 19, which is freely connected by passages 23 with the interior 22 of the stem 14. A fuel nozzle 26 is mounted within the stem 14 above the 35 chamber 21, and is supplied with fuel from the chamber 10 through diagonal fuel passages 30. The passage 22 within the stem 14 communicates at its upper end with the mixing chamber 16, and the nozzle 26 lies 40 axially within this passage and is provided near its upper end with lateral passages 28. The supply of fuel through these passages is controlled by a needle valve 31, which is guided by the upper end 26' of the bore of 45 the nozzle 26. The valve stem 31 extends upward freely through a protective tube, so that the valve may be reciprocated vertically therethrough. The valve 31 is provided at its upper end with a ball head 37, which is 50 mounted in an adjusting screw 41, said screw having an interior chamber 42 in which is mounted a light spring 43 which presses the ball 37 lightly downward. The adjusting screw 41 is threaded into a vertically recip-

rocable block 45, which is mounted in the 55 interior of a boss 46 carried by the upper wall of the main body 15. A light spring 47 acts upon the block 45 to drive it downwardly.

Pivoted at 51 within chamber 16 is a lever 60 52 carrying a yoke 53, which is pivoted to the lever on a pivot 54 at right angles to the pivot 51 and is provided at its ends with rollers or fingers 55 which project under and engage with the lower end of block 45. 65 The opposite end of lever 52 is provided with a roller or bearing piece 56 which takes under a range 57 carried by the stem 58 of the auxiliary air inlet valve 59. The stem 58 of valve 59 is centrally bored at 61 to 70 receive a guide pin 62 on which fits a washer 63, between which and the lower end of stem 58, is mounted a spring which normally urges the valve 59 upwardly against its seat 65. The tension of spring 64 against the 75 valve 59 may be readily adjusted by means of a temper screw 66 which carries and is preferably integral with the guide pin 62 and is threaded through the lower wall of casing 15 so as to form an adjustable abutment for washer 63. This temper screw may be held in any desired position of adjustment by the set screw 67.

In the commercial manufacture of carbureters for general use, I have found that 85 much difficulty is experienced by individual users of carbureters where ordinary tests of such carbureters indicate that they are properly designed to produce proper fuel mixtures and such apparently erratic results 90 have been a source of continual puzzle to the commercial manufacturers of carbureters. I have now found to be untenable the theory which has heretofore commonly obtained 95 that individual makes of engines do not materially affect, by reason of their cylinder proportions and speeds, the action of carbureters and I have found that, on the contrary, each particular type of engine has apparently unexplainable idiosyncrasies of 100 effect upon a carbureter at various speeds. In order, therefore, to be able to produce a carbureter having in general a fixed form as to its several parts so that it may be manufactured cheaply in large numbers, and yet 105 so that it may be readily adapted for different types of engines, I have so constructed my present carbureter that, while it may be

standard as to most of its parts, I may readily supply the standard portion with an air inlet nozzle particularly designed empirically for the particular type of engine to which the carbureter is to be attached. For this purpose therefore, I have provided the upper wall of the casing 15 with a circular seat or socket 71 into which may be fitted any one of a number of air inlet nozzles 72. 5

10 Each of these nozzles is provided at its outer end with an inwardly projecting annular valve seat 65 against which the valve 59 normally rests. From this seat 65 inwardly the nozzle 72 is flared, or increased in diameter, as shown at 73. The exact conformation of the flared portion 73 I determine empirically by attaching the carbureter to an engine of given type; running the same at different speeds and determining by experiment the space or air passage which should be had for the most efficient mixture when the valve 59 is, by the suction of the engine at that particular speed, moved downwardly away from seat 65. 15

20 25 By providing the main casing with a seat for the reception of any desired air inlet nozzle, it will be seen that it is possible for me to produce a standard carbureter which may then be especially adapted for an engine of any particular manufacture or type by merely supplying the standard carbureter structure with the special air inlet nozzle which I find by experiment to be the best adapted to that particular type of engine. 30

35 40 In operation, screw 41 is so adjusted in block 45 that valve 31 will be adjusted relative to the nozzle 26 to a point where at the low speeds of the engine when sufficient air therefor can be drawn through the primary air inlet 19, there will be just sufficient gasoline supplied through passages 28 past the valve 31 to give proper quantities of fuel to the air passing inwardly through the inlet structure 19. In all positions of adjustment 45 the block 45 rests upon rollers 55 of lever 52. As the speed of the engine is increased, valve 59 will be drawn downwardly against the action of spring 64 so as to admit an additional quantity of air which must be supplied with a sufficient quantity of fuel by producing a richer mixture of fuel with the air coming in through the primary inlet 19, and consequently, as the valve 59 is moved inwardly by the suction of the engine, lever 55 50 is swung by the inward movement of the valve so as to raise the needle valve 31 and thus permit a greater quantity of fuel to be delivered to the air passing upwardly from the primary inlet 19 through the passage 22. 55

60 65 The screw 41 will be ordinarily adjusted for the particular engine to which the carbureter is applied and for ordinary or average weather conditions and this adjustment is not intended to be often changed. 70

65 In order to prevent sudden fluctuations of valve 59 I provide a dash pot retarder therefor comprising cylinder 91 and piston 92 which fits the cylinder in such manner as to offer some slight resistance to movement in either direction. Piston 92 is provided with a stem 93 which must fit the guiding bearing 94 tightly enough to prevent the passage of air to or from the cylinder. A rigid connection between stem 93 and valve 59 would require extreme accuracy of alinement of the cylinder and valve support and would thus make the cost of production commercially prohibitive. In order to avoid this difficulty, therefore, I connect stem 93 to valve 59 by a free ball-and-socket joint 95 75 and then counterbore stem 58 so that only its lower end touches the guide pin 62. The length of contact between the guide pin 62 and that part of the bore in the stem 58 which is not counterbored is sufficiently 80 short, and the joint between such parts is sufficiently loose, to permit slight disalinement. Cylinder 91 is carried by a cage or support 96 which may be threaded or otherwise secured to the upper end of any air-inlet nozzle 72 which may be attached to the carbureter body. 85

90 I claim as my invention:

1. In a carbureter, the combination with the main body having an air inlet provided with an inwardly opening valve seat, an air valve arranged within said body and associated with said valve seat, a guide stem projected into an axial bore of the valve, said axial bore exceeding the diameter of the 95 guide stem except for a sufficiently short distance at the entrance end of the bore to allow slight disalinement and the guide stem projecting past the smaller portion of the bore into the larger portion thereof, a spring 100 arranged to act axially upon the valve to drive it to its seat, a dash pot arranged in substantial alinement with the valve, a piston mounted in said dash pot, a stem carried by said piston, a bearing for said stem, and a flexible positive connection between said piston and the valve. 105

110 2. In a carbureter, the combination with the main body having an air inlet provided with an inwardly opening valve seat, an air valve arranged within said body and associated with said valve seat, a guide stem projected into an axial bore of the valve and sufficiently loose therein to permit slight disalinement, a spring arranged to act axially upon the valve to drive it to its seat, a dash pot arranged in substantial alinement with the valve, a piston mounted in said dash pot, a stem carried by said piston, a bearing for said stem, and a flexible positive connection between said piston stem and the valve. 115

120 125 3. In a carbureter, the combination with the main body having an air inlet provided with an inwardly opening valve seat, an 130

- air valve arranged within said body and associated with said valve seat, a guide stem projected into an axial bore of the valve, said axial bore exceeding the diameter of the guide stem except for a sufficiently short distance at the entrance end of the bore to allow slight disalignment and the guide stem projecting past the smaller portion of the bore into the larger portion thereof, a spring arranged to act axially upon the valve to drive it to its seat, a second stem and bearing therefor, and a flexible connection between said second stem and the air valve.
4. In a carbureter, the combination with the main body having an air inlet provided with an inwardly opening valve seat, an air valve arranged within said body and associated with said valve seat, a guide stem projected into an axial bore of the valve, said axial bore exceeding the diameter of the guide stem except at the entrance end of the bore, a spring interposed between the valve and the guide stem to normally drive the valve to its seat, an adjusting screw mounted in the main body and forming an adjustable support for the guide stem, a dash pot, a stem carried by said piston, a bearing for said stem, and a flexible connection between said stem and valve.
5. In a carbureter, the combination with the main body having an air inlet provided with an inwardly opening valve seat, an air valve arranged within said body and associated with said valve seat, a guide stem projected into an axial bore of the valve, said axial bore exceeding the diameter of the guide stem except at the entrance end of the bore and the guide stem projecting past the smaller portion of the bore into the larger portion thereof, a spring interposed between the valve and the guide stem to normally drive the valve to its seat, an adjusting screw mounted in the main body and forming an adjustable support for the guide stem, a dash pot, a stem carried by said piston, a bearing for said stem, and a flexible connection between said stem and valve.
6. In a carbureter, the combination with the main body having an air inlet provided with an inwardly opening valve seat, an air valve arranged within said body and associated with said valve seat, a guide stem projected into an axial bore of the valve, a spring interposed between the valve and the guide stem to normally drive the valve to its seat, an adjusting screw mounted in the main body and forming an adjustable support for the guide stem, a dash pot, a stem carried by said piston, a bearing for said stem, and a flexible connection between said stem and valve.
7. In a carbureter, the combination with the main body having an air inlet provided with an inwardly opening valve seat, an air valve arranged within said body and associated with said valve seat, a guide stem projecting into an axial bore of the valve, a spring interposed between the valve and the guide stem to normally drive the valve to its seat, an adjusting screw mounted in the main body and forming an adjustable independent support for the guide stem, a second stem and bearing therefor located on the opposite side of said valve from said guide stem, and a flexible connection between said second stem and the air valve.
- In witness whereof, I have hereunto set my hand and seal at Indianapolis, Indiana, this twenty-fourth day of June, A. D. one thousand nine hundred and twelve.
